UNITED STATES PATENT OFFICE

172,463

ELECTRIC LAMP BASE

David Borowitz, Chicago, Ill., assignor to Bradley Manufacturing Company, Chicago, Ill., a corporation of Illinois

Application December 23, 1953, Serial No. 28,186

Term of patent 3½ years

(Cl. D48—20)

To all whom it may concern:

Be it known that I, David Borowitz, a citizen of the United States, residing at Chicago, Illinois, have invented a new, original, and ornamental Design for an Electric Lamp Base, of which the following is a specification, reference being had to the accompanying drawing, forming a part thereof.

In the drawing:

Fig. 1 is a front elevational view of an electric lamp base embodying my new design, with the socket shown in dotted lines, broken away; and

Fig. 2 is a top plan view thereof, the socket being omitted for convenience of illustration.

The rear and side views would be the same as the front view.

The dominant features of my present design lie in the portions shown in full lines.

I claim:

The ornamental design for an electric lamp base, substantially as shown and described.
